D. F. Quigley Inventor

By Watson E. Coleman
Attorney

UNITED STATES PATENT OFFICE.

DANIEL F. QUIGLEY, OF BANGOR, MAINE.

FIRE-ALARM SYSTEM.

Application filed February 16, 1928. Serial No. 254,762.

This invention relates to fire alarm systems and more particularly to a circuit closing element for an electrical alarm system.

An important object of the invention is to provide a device of this character which may be very readily and cheaply produced and is readily installed and which, when installed, will have more or less the appearance of an ordinary electric light globe, so that it is not unsightly in appearance.

A further object of the invention is to provide a switch element for electrically operated fire alarm systems having means augmenting dangerous increases of temperature to insure a prompt and immediate operation of the alarm and rapid closing of the switch.

A further object of the invention is to produce a device of this character which may be housed so that it is normally hidden from view and in which the construction is such that the housing may be made of readily inflammable material, so that in event of contact of flame therewith, this cover will act as an agent, promoting the rapidity of closure of the switch.

These and other objects I attain by the construction shown in the accompanying drawing, wherein for the purpose of illustration is shown a preferred embodiment of my invention and wherein:

Figure 1 is a side elevation of a circuit closer for automatic electrical fire alarms constructed in accordance with my invention, the cover being shown in section;

Figure 2 is a longitudinal sectional view through the circuit closer;

Figure 3 is a section on the line 3—3 of Figure 2.

Referring now more particularly to the drawing, the numeral 10 generally designates a base of insulation having extended therefrom at one side a pair of bars 11 which, when subjected to variations in temperature, flex, and when heated, approach one another.

Carried by the outer ends of these bars are contact elements 12 which are adjustably mounted in the bars, as indicated at 13, so that the extent through which the bars must flex may be adjusted. These bars preferably have their inner ends reduced and extended through the material of the base, so that they project and form the contact tongues 14 for engagement with an ordinary connection socket 15.

The outer face of the base or that face from which the bars 11 project is provided

with means for mounting fuses or matches 16, there preferably being three matches, one arranged between the bars and the others arranged at the outer faces thereof. These matches are in close proximity to the bars, so that when burning, the heat thereof will be readily transmitted to the bars.

The base 10 forms a means for supporting a cover 17 housing the bars 11 and matches 16. This cover is perforated, as indicated at 18, to permit ready circulation of air therethrough and is preferably formed of some readily inflammable material, such as celluloid. It will be obvious that the circuit may be installed employing the ordinary plug fixtures and that the devices, when applied thereto, will have substantially the appearance of an electric light globe. When subjected to intense heat, this heat will cause flexing of the bars 10 and closure of the circuit. In many instances, particularly where direct contact of flame occurs, the fuses or matches 16 and cover 17 will become ignited, generating an intense heat, which will cause the action of the bars to be substantially instantaneous.

Since the construction hereinbefore set forth is capable of a certain range of change and modification without materially departing from the spirit of the invention, I do not limit myself to such specific structure except as hereinafter claimed.

I claim:

1. A switch element for electrical fire alarm systems comprising a base having thermo-metallic bars adapted to be connected in the circuit of the fire alarm and provided with contact elements engaging when the bars are heated, and means associated with said base and operative under extreme temperatures for producing flame in direct contact with said bars.

2. A switch element for electrical fire alarm systems comprising a base having thermo-metallic bars adapted to be connected in the circuit of the fire alarm and provided with contact elements engaging when the bars are heated, and means associated with said base and operative under extreme temperatures for producing flame in direct contact with said bars comprising matches carried by said base and substantially paralleling the bars.

3. A switch element for electrical fire alarm systems comprising a base having thermo-metallic bars adapted to be con-

- nected in the circuit of the fire alarm and provided with contact elements engaging when the bars are heated, and means associated with said base and operative under 5 extreme temperature for producing flame in direct contact with said bars comprising an inflammable cover carried by the base and surrounding and concealing said bars.
4. A switch element for electrical fire 10 alarm systems comprising a base having thermo-metallic bars adapted to be connected in the circuit of the fire alarm and provided with contact elements engaging when the bars are heated, means associated 15 with said base and operative under extreme temperatures for producing flame in direct contact with said bars comprising matches carried by said base and substantially paralleling the bars, and an inflammable cover 20 carried by the base and surrounding and concealing said bars and matches.
5. A switch element for electrical fire
- alarm systems comprising a base having thermo-metallic bars adapted to be connected in the circuit of the fire alarm and 25 provided with contact elements engaging when the bars are heated, and means associated with said base and operative under extreme temperatures for producing flame in direct contact with said bars, the ends of 30 said bars being extended through the base to form tongues for engagement in a plug fixture.
6. A switch element for electrical fire 35 alarm systems including a base, a thermo-metallic bar carried thereby and flexing when heated to electrically engage a contact, and means associated with said base and operative under extreme temperatures for producing flame in direct contact with said 40 bar.

In testimony whereof I hereunto affix my signature.

DANIEL F. QUIGLEY.
